Application April 25, 1934, Serial No. 722,281

2 Claims. (Cl. 171—119)

My invention relates to apparatus for adjusting the voltage of alternating-current electrical circuits, and it has particular relation to equipment capable of effecting such adjustment in a plurality of steps without interrupting the load current of the circuit.

In maintaining constant the voltage supplied to load centers through distribution or feeder circuits, regulating apparatus is required to compensate for variations in the voltage of the power source and for changes in the circuit-impedance drop which result from load-demand fluctuations. My invention is directed to a step-type of voltage adjustor or regulator which because of its low-cost and other desirable characteristics is particularly well suited for application to feeder circuits of the relatively high-voltage low-current ratings which are so prevalent in present-day rural, suburban and certain other distribution systems.

One object of my invention is to reduce the cost of equipments for regulating the voltage of alternating-current circuits.

Another object of my invention is to simplify step-type regulators involving multi-tap transformer windings and underload tap-changing mechanisms.

A further object of my invention is to reduce the capacity of the regulating transformer equipment required by a given installation by employing switching means adapted to reverse the connections of the regulating-component supply winding.

An additional object of my invention is to provide a load tap changer mechanism which requires only a small amount of space and which changes taps with the simplest possible mechanical means.

A still further object of my invention is to provide improved mechanical means for actuating the tap-changer and the switches which serve to shift the component-supply winding from one to the other of two voltage-controlling ranges.

45 The voltage-adjusting equipment of my invention essentially comprises, for each phase of the circuit to be regulated, a special regulating transformer having an exciting winding, which need be of but small capacity, energized by the circuit voltage and a multi-tap series winding adapted to introduce corrective components into the circuit. To adjust the magnitude of these components without interrupting the circuit current, an underload tap changer is provided and to 55 change their direction from "buck" to "boost",

as conditions may require, reversing switches, adapted to be actuated when the tap-changer occupies the zero component value position, are utilized. With this particular arrangement of the windings and associated switches, I have 5 found it possible to effect adjustment through a given range with a transformer having considerably less kilovolt ampere rating than that formerly required. Preferably, the tap-changer and reversing switch assemblages, marked im- 10 provements in the mechanical design of which my invention contemplates, are built into a single compact unit which may be integrally fixed to the housing structure of the associated transformer apparatus.

15 My invention itself, together with additional advantages thereof, will best be understood through the following description of a specific embodiment when taken in conjunction with the accompanying drawings, in which:

20 Figure 1 is a perspective view showing the external appearance of one preferred form of the voltage-regulating equipment of my invention when designed for application to a three-phase circuit;

25 Fig. 2 is a diagrammatic view of the apparatus and circuits comprised by each circuit phase of the regulating equipment of Fig. 1;

Fig. 3 is a chart showing the sequence of operation of the several switches utilized by the 30 tap-changing and winding-connection reversing mechanisms of the system of Fig. 2;

35 Fig. 4 is a diagrammatic view of apparatus and circuits modified to regulate a circuit, the current in which exceeds the rated capacity of 35 the corrective-component supply winding and associated tap-changer;

40 Fig. 5 is a diagram showing one manner in which three of the assemblages shown in Fig. 2 may be combined, as in the unit of Fig. 1, to effect regulation of a three-phase circuit.

Fig. 6 is a view taken on a horizontal section through the integral unit of Fig. 1 showing how the parts therein are constructed and arranged;

45 Fig. 7 is a sectional view taken on the line VII—VIII of Fig. 6 illustrating the mechanical details of the improved tap-changing and reversing-switch assemblages comprised by the equipment of Figs. 1 and 6;

50 Fig. 8 is a sectional view taken on the line VIII—VIII of Fig. 7 showing the operating mechanism for the reversing switches of Figs. 1, 6 and 7;

55 Fig. 9 is a sectional view taken on line IX—IX of Fig. 7 showing the construction of the tap

changer switches of Figs. 1, 6 and 7 and their operating mechanism;

Fig. 10 is a sectional view taken on line X—X of Fig. 7 showing similar details of the reversing switches; and

Fig. 11 is a diagrammatic view illustrating the manner in which the tap-changer and reversing-switch mechanisms are interconnected with the windings of the main regulating and the tap-bridging transformers comprised by each circuit phase of the previously illustrated equipment.

Referring first to Fig. 2 of the drawings, the voltage-adjusting means of my invention are there diagrammatically represented as comprising, for each phase of the circuit to be regulated, a transformer having an exciting winding 12, connected to receive energization from the voltage acting in the supply side of the circuit, designated by conductors 13 and 15, and a series winding 14 inductively related to the first-named winding and adapted, through the utilization of tap-changing means 16 and reversing switch means 18, to interconnect the supply conductor 13 with one of the conductors 17 of the regulated circuit 17—15.

The tap-changing means 16 are associated with the winding 14 which is provided with a plurality of taps designated as *a* to *e*, inclusive, which are respectively connected with switch segments A to E, with which segments a pair of movable members X and Y, joined with the ends of a tap-bridging auto-transformer winding 20, are adapted to selectively cooperate. The series connection of winding 14 with the regulated circuit includes one end 22 of the winding, the mid-point 23 of the tap-bridging winding 20, and switches J, K, L and M, comprised by the connection reversing means 18. By properly actuating, as in the sequences set forth by the table of Fig. 3, the tap-changing and reversing switches, the voltage of the regulated circuit may, in the case of the five-tap winding shown, be varied with respect to that of the supply circuit in nine separate steps.

In the improved system of my invention about to be described, the tap transfer switches, involving the bridging winding segments X and Y and the series winding tap segments A to E, inclusive, perform all of the load switching operations so that all arcing is confined to these switches. The reversing switches J, K, L and M merely reverse the series section 14 of the regulating auto-transformer winding as the tap changer passes through the neutral position. Since the voltage across these switches is practically zero when they are operated, no arcing takes place at their contacts. Furthermore, with this method of changing taps the number of transformer tap leads required for a given number of operating positions is only one more than half the number of those positions and an equally reduced number of load switches only are required per phase. The tap-bridging winding 20 is, in addition, short-circuited on each operating position, thereby eliminating its exciting current and resistance loss except during the transition period while changing taps.

In the chart of Fig. 3, the presence of a circle indicates a closed switch and the absence of a circle similarly indicates an opened switch. Thus, in the first position of the voltage-adjusting mechanism, which is indicated in the left-hand column of the chart of Fig. 3 under the numeral 1, the tap-changing switches X—A and

Y—A are closed, as are also the reversing switches J and L, and all of the remaining switches in the system are in their circuit-opened positions.

For this closure combination, the full length of winding 14 is connected between the conductor 13 of the supply circuit and the conductor 17 of the regulated circuit, this connection being such that the voltage induced in winding 14, as a result of the flux produced by the exciting winding 16, aids or directly adds to that of the supply circuit and thereby increases the potential appearing between the regulated-circuit conductors 15 and 17. When the equipment occupies position No. 1, therefore, there is produced in the regulated circuit a maximum value of voltage for a given supply circuit potential. In this position, as well as in each of the eight others, the tap-bridging winding 20 is shunted through the tap segment with which switch segments X and Y are simultaneously connected.

To reduce by one step, corresponding to the distance between the taps *a* and *b* of winding 14, the voltage introduced by this winding into the regulated circuit, the adjusting equipment is actuated to position No. 2. During such actuation, segment Y is first shifted from tap segment A to tap segment B, and segment X then follows with a similar transfer the completion of which places the equipment in the new position.

Still further reductions in the regulated voltage may be effected by advancing the equipment to position No. 3, in which the active connection is shifted to winding tap *c*, and thence to position No. 4 in which the connection is made with tap *d*. In position No. 4, only the voltage appearing between taps *d* and *e* is introduced into the regulated circuit. To make the voltage exactly equal to that of the supply side of the circuit the equipment is further advanced to position No. 5 in which the segments X and Y are caused to contact tap segment E, which being connected with the end 22 of winding 14 reduces the component of corrective voltage to zero. In this position it will be noted that reversing switches K and M have also been closed, this closure taking place in a circuit already completed through switches J and L and hence between different parts of which substantially no voltage appears.

To reduce the regulated voltage below that of the supply side of the circuit, the equipment is advanced to position No. 6. This advancement includes an opening of reversing switches J and L, which opening allows the active winding circuit to be routed in the opposite direction through reversing switches K and M. As a result of this connection reversal, the voltage of the winding 14 is introduced into the system in a manner that it opposes or bucks the supply circuit voltage, so that when the equipment has advanced to position No. 6, in which the bridging transformer segments X and Y contact series windings tap segment D, the regulated voltage is reduced by one step.

Further advancement of the equipment to position No. 7 increases the reduction by another step to which may be added additional steps by further advancements to position Nos. 8 and 9. In position No. 9, in which the active connection is established through winding tap *a*, the full length of the winding 14 is effective in reducing the regulated voltage with respect to that of the supply side of the circuit.

To progressively raise the regulated circuit

voltage, the equipment may be actuated from position No. 9 to position No. 1, through a series of operations which are exactly the reverse of those just described.

The system of Fig. 2 requires that the series winding 14 of the main regulating transformer and also the tap changing and reversing switches associated therewith be capable of carrying the full load current of the regulated circuit. For the relatively high voltage, low current distribution circuits previously referred to, this presents no difficulties in design and permits of a very economical and satisfactory equipment. The method just described is, however, also applicable to the regulation of circuits in which the current rating exceeds that of the adjusting apparatus. One preferred manner of applying the apparatus to such a high current circuit is illustrated in Fig. 4 in which a series transformer 28 is interposed between the circuit and the adjusting apparatus. For such a combination no separate series winding section is required and the taps may be made directly to the single shunt-connected winding 30 of the regulating transformer. The sequence chart of Fig. 3 applies to the system illustrated in Fig. 4 as well as to that in Fig. 2. Since the system of Fig. 2 is the one most commonly utilized, the preferred mechanical arrangement of parts and improved equipment designs of my invention will be described in connection therewith.

In the explanation of such preferred forms of mechanical construction, I have illustrated an equipment adapted for the regulation of a three-phase circuit, which equipment comprises three of the regulating-transformer, tap-changing and reversing-switch combinations shown in Fig. 2 interconnected in suitable manner as illustrated in Fig. 5. Thus, each of the three phases of the circuit is provided with the regulating transformer comprising shunt and series windings 12 and 14, the tap changing equipment 16 and the reversing switches 18. The exciting windings 12 are connected for energization from the conductors 32 of the supply side of the circuit, while the series windings 14 are adapted for connection between these conductors and the conductors 34 of the regulated side of the circuit. Switch actuating equipments arranged to effect parallel operation of the switches in each of the three groups are suitably provided.

All of this equipment is housed inside of a sheet metal tank structure, the external appearance of a preferred design of which is illustrated in Fig. 1. Protruding from the top of the structure are a plurality of insulator-supported terminals 38 through the medium of which the supply and regulated circuit conductors, represented at 32 and 34 in Fig. 5, are connected with the windings of the transformers housed inside of the rear portion 36 of the structure and the transfer and reversing switches mounted in a separate compartment 46 which is formed integral with one side of the transformer compartment which is adapted to be filled with insulating oil and which is provided with the usual cooling or radiator tubes 40.

The view of Fig. 6, taken along a horizontal section through the structure of Fig. 1, illustrates one preferred manner of arrangement of the apparatus comprised by the complete voltage adjusting equipment. The three regulating auto-transformers, each of which comprises the before-described windings 12 and 14, are positioned side by side in the rear tank compartment 36,

as indicated by the outlines 42. Also mounted in this compartment are the tap bridging auto-transformers, each of which comprises the before described winding 20, indicated in Fig. 6 by the outlines 44.

Integrally fixed to one side of this transformer housing structure is the auxiliary compartment 46 which serves to house the tap changing and reversing switch assemblies. This switch compartment is also adapted to be filled with insulating oil. An inspection plate 48 is provided on the front as is also an opening 50 through which a position indicating dial, shown at 52 in Fig. 7, may be viewed.

In addition, the equipment illustrated in Figs. 1 and 6 comprises a third compartment or housing 54 in which automatic control apparatus is positioned. Since this apparatus of itself forms no part of the present invention, no detailed showing or description of it is herein made.

As is shown by Figs. 6 to 10, inclusive, in which the adjusting apparatus is illustrated as occupying its position No. 5, the segments A to E of each of the tap-changing equipments 16, which segments are connected with the taps of the series winding 14 of each of the regulating transformers, are in the form of protruding metal plates mounted upon a vertically positioned panel or strip 56 of insulating material, while the associated movable fingers X and Y, connected to the ends of each tap-bridging transformer winding 20, are carried by a panel 58 of insulating material which is supported by bracket members 60. These members cooperate with a vertically mounted worm shaft 62 which, when rotated, causes them, together with the equipment attached thereto, to move vertically.

The main drive shaft 62 is provided with two independent screw-like grooves best shown in Fig. 9 at 85 and 86, the one of which, as the shaft is rotated in a given direction, serves to move the cooperating brackets 60 downwardly to their illustrated lower limit of travel at which time control thereof is transferred to the second of the grooves which serves upon continued rotation of the shaft in the same direction to move the members 60 upwardly along the length of the shaft.

In operation of the tap changer, the shaft 62 may be driven in any suitable manner as manually or through the medium of a motor 88 shown in Fig. 7 as interconnected with the shaft through the medium of suitable reduction gearing. This motor may be controlled by means of the apparatus housed inside of the control compartment 54 (Figs. 1 and 6). The before-mentioned position indicating disk 52 is connected through suitable gearing to be moved in accordance with the rotation of shaft 62.

Likewise, the reversing switch equipment 18 for each of the circuit phases comprises two conducting material disk members 64 and 66 which are carried by a second vertically mounted shaft 68, which, when rotated, causes these members to jointly or selectively interconnect sets of cooperating contact members 70 and 71, respectively, which are mounted upon a strip of insulating material 72, with the associated sets of contact members J and M 70 and L and K which are similarly mounted upon spacedly positioned insulating material strips 73 and 74.

The reversing switch shaft 68 is mechanically interconnected with the first-named shaft 62

through a train of gears comprising, as is best shown in Figs. 7 and 8, a pinion member 76, a cooperating gear 77, a second pinion 78, and a gear 79 meshing therewith. This last named gear is mounted upon a shaft 80 which carries a disk member 81 near the periphery of which a pin member 82 is mounted. This pin is adapted to fit into a slot 83 in a Geneva-gear element 84, which is mounted upon the reversing switch shaft 68, and serves to impart motion thereto in a manner to be further explained.

The connections indicated by the simplified diagram of Fig. 11 are established between the 15 transformers, housed in the rear compartment 36 of the regulating unit, and the switching devices, housed in the front compartment 46, through the medium of insulated conductors. Thus the taps *a* to *e* of the series winding 14 20 of each of the transformers are connected by means of leads 90 (Fig. 9) to the stationary segments A to E, inclusive. Similarly, connection from the ends of each tap-bridging transformer winding 20 are made with the movable 25 contact segments X and Y through the medium of leads 91 which are attached to a pair of vertically positioned metal strips 92 and 93 against which strips contact fingers 94 and 95, respectively connected with segments X and Y, 30 are respectively adapted to slidably bear. These fingers are supported from the movable panel of insulating material 58 before mentioned.

Each set of reversing switches, comprising the disk members 64 and 66, is interconnected with the 35 transformer windings and the circuit conductors through the medium of leads 97 in the manner indicated in Figs. 10 and 11. These connections are so made that when the switch disks occupy the intermediate position illustrated, contact finger 70 is electrically connected with both of the associated fingers J and M and finger 71 is similarly connected with the associated fingers L and K. Rotation of the shaft 68 in a counterclockwise direction interrupts the 40 connection of fingers K and L while rotation of the disk carrying shaft in the clockwise direction similarly interrupts the connection of fingers M and K.

Since in Figs. 6 to 11, inclusive, the switching 50 apparatus is illustrated as occupying position No. 5, the carriage panel 58 is there represented at the lower limit of its travel and the reversing switch segments are in their intermediate positions. This combination produces the circuit 55 closures indicated under column 5 of the sequence chart of Fig. 3, for which combination, the voltage of the regulated side of the circuit is equal to that of the supply side, no corrective component being introduced by the series windings 14.

Rotation of the drive shaft 62 causes the carriage assemblage, including contact fingers X and Y, to move upwardly, thereby shifting the connections of tap winding 20 from tap 60 segment E to D, C, B or A. When the shaft rotation is in one direction, the pin 82, in being rotated by the shaft 80 through the gear mechanism before described, shifts the Geneva gear member 84 to one side of its neutral position, thereby causing the reversing switch disks 64 65 and 66 to connect the winding 14 in boosting relation to the supply circuit. Similarly, a rotation of the shaft 62 in the opposite direction causes the reversing switch disks 64 and 66 to reverse this connection so that the voltage of

winding 14 backs or opposes that of the supply circuit.

In both instances, the operation of the reversing switches takes place in a circuit of substantially zero voltage so that there is no arcing 5 at the switch contacts. In other words, the connection at the reversing switches is changed before the contact members X and Y have been biased upwardly into active contact with tap segment D.

This operation having been effected, the pin 82 moves out of the slot 83 in the Geneva gear member 84 and does not again contact it until the tap changing equipment has been returned to closely approach position No. 5, at which 15 time re-entry of the pin into the slot takes place, and upon a continuance of rotation of the worm shaft 62, the reversing switch segments are returned to their intermediate position and rotated in the opposite direction and 20 to their other limiting position in which the winding 14 is reversed in its connection between the supply and regulated circuits.

In connection with the tap-changing mechanism, it is to be noted that each of the 25 stationary mounted tap segments A to E, inclusive, is of a length slightly greater than the spacing between the cooperating movable contact members X and Y, and that the spacing between the adjacently positioned tap segments is slightly less 30 than the spacing between members X and Y. As a result, when the illustrated equipment is in any one of its nine operative positions, both ends of the tap bridging winding 20 are connected to the same stationary tap segment and 35 the resulting desired short-circuiting of the bridging winding is thereby effected without the use of the special or separate switch which heretofore has been required.

As contact members X and Y are advanced 40 from one stationary tap segment to the next, the leading member contacts the adjacent segment before the lagging member leaves the original segment and in this manner accomplishes the desired tap bridging operation. For the intermediate or transition positions of the equipment, the active circuit through the apparatus is thus established through but one-half of the bridging winding 20, which active circuit is supplemented by a path through the second or other half of 50 the bridging winding as soon as the operating or full-on tap position of the equipment has been reached.

Although the means for rotating the shaft 62 of the switching assemblage forms no part 55 of the present invention, it may here be pointed out that when a motor such as is shown at 88 in Fig. 7 is utilized to rotate the shaft, the control means for the motor will include, in addition to operation initiating equipment, apparatus adapted to discontinue its operation as soon as it has advanced the switching equipment to the succeeding full-on tap position. In case the correction thereby effected by this single step is insufficient, initiation of motor operation will 60 again be effected for continuance during a succeeding step. In this manner, it is assured that the equipment will stop only when in the full on-tap positions.

Since all arcing is confined to the tap segments A to E, inclusive, and their cooperating movable members X and Y, the reversing switches may be made of a simpler and less expensive design than were they too to be subjected to arcing duty.

Preferably, as has already been indicated, the casing 46 in which the switching devices are housed is adapted to receive insulating oil, the presence of which oil not only functions to effectively quench any arcs which tend to be set up at the tap changing switch contacts, but also serves to properly lubricate the moving parts comprised by the several switches and their actuating mechanisms.

10 Although I have shown and described a certain specific embodiment of my invention, I am fully aware that many modifications thereof are possible. My invention, therefore, is not to be restricted except insofar as necessitated by the prior art and by the scope of the appended claims.

I claim as my invention:

1. Regulating apparatus for adjusting the portion of a multi-tap transformer winding which is in active connection with an electrical circuit and for reversing the connection when said active winding portion is adjusted to zero comprising, in combination, tap-changing means which include a plurality of contact segments 25 respectively connected with the winding taps and stationarily mounted in spaced straight-line relation, cooperating contact fingers, a movable member for supporting said fingers in engageable relation with the segments, and a shaft 30 adapted to parallel said line of contact segments and to threadedly engage said movable member in a manner that when rotated it shifts the

contact fingers through their extreme position at one end of the segment line in which the winding portion in active circuit is zero, means, comprising switches, for reversing the winding in its connection with the circuit, a reversing- 5 switch actuating shaft, and means, comprising a Geneva-gear connection between said two shafts, whereby a movement of the shaft first-named through its said zero-winding portion range effects a switch-actuating movement of 10 the second-named shaft.

2. Apparatus for changing from one to another of the taps of a multi-tap transformer winding the connection with a current-carrying electrical circuit comprising, in combination with 15 a tap-bridging impedor, a plurality of contact segments respectively connected with the winding taps and stationarily mounted in, spaced straight-line relation, a pair of impedor-connected contact fingers, a movable member for 20 spacedly supporting said fingers in engageable relation with said segments, and a shaft positioned to parallel said line of contact segments and adapted to threadedly engage said movable member in a manner that when rotated in 25 a given direction it effects a shifting of the contact fingers from an extreme position at one end of the line of contact segments to a corresponding position at the opposite end of the line and then back to the first-named position. 30

FRANKLIN L. SNYDER.
